HAIR CAP FOR BALD OR SPARSELY HAIR ED HEADS

George Frederick Hull, Yalourn, Victoria,
AustraliaApplication September 2, 1950, Serial No. 182,909
In Australia May 23, 1949

5 Claims. (Cl. 132—53)

1

This invention relates to a hair cap to comprise a covering for a bald or sparsely haired head.

In order to conceal baldness or hairlessness it is established practice to employ an artificial head covering known generally as a "wig" and comprised of a backing or frame to which hair of required colour is attached.

Such wigs or hair coverings unless very well made and fitted, are unsightly, and being fragile and easily damaged require to be carefully handled. Moreover, the artificial nature of a wig is difficult to conceal, and a wig is apt to become displaced and cause discomfort and uneasiness to a wearer. Furthermore, hair is apt to become detached in places, which makes the artificial character of a wig more apparent.

Now the principal object of this invention is to provide a hair cap for a bald or sparsely haired head which is durable and of good and natural appearance, provides comfort and confidence for a wearer, cannot become loose and accidentally detached, provides a controlled outlet for perspiration and vapour, readily conforms with movements of the scalp, and can be produced at low cost.

In achieving the above stated principal object and according to the broadest concept of the invention, a hair cap for a bald or sparsely haired head, comprises an inner scalp-fitting layer of soft flexible non-absorbent acid resistant material fitting the normal hair growing area of the head, an outer hair-holding layer of flexible material overlying and adhesively united with the inner scalp-fitting layer, and apertures for escape of perspiration and vapour extending through the inner and outer layers.

In a more specific construction, the material forming the inner and outer layers, comprises a suitable plastic, such as polyvinyl chloride, and the inner and outer layers are adhesively united by the use of an appropriate solvent.

A further object of the invention is the provision of means for firmly securing the hair in the outer hair-holding layer.

In attaining this further object, the outer layer is formed with countersunk apertures, the countersunk recesses being on the inner surface of the layer and backed by the inner layer and the hair being contained in groups or bundles in thin tubes of aluminium fitting the apertures, the tubes being bent to hold the hair and headed or enlarged to fit within the countersinks to thereby positively secure the hair and tubes against displacement.

2

The invention will be better understood from the description of the illustrative embodiment of a hair cap or covering depicted in the accompanying drawings.

5 In these drawings:

Fig. 1 is a view in perspective showing the hair cap as fitted to a wearer's head.

Fig. 2 is a perspective view of the back of the wearer's head with a portion of the hair cap shown sectionally with the hair removed.

10 Figs. 3 and 4 are respectively a fragmentary section and plan of the inner head-contacting part of the hair cap, drawn on an enlarged scale.

Figs. 5 and 6 are respectively a fragmentary section and plan on an enlarged scale of the outer hair-holding part of the hair cap.

15 Fig. 7 is a sectional elevation of a tubular hair containing unit preparatory to forming and incorporation in the hair cap.

20 Fig. 8 is a fragmentary sectional detail of the hair cap.

Fig. 9 is a view in perspective of an instrument for facilitating detachment or lifting of the hair cap.

25 Referring to these drawings in more detail, the numeral 5 indicates in general the hair cap or covering comprising an inner layer or interior scalp cap 6 of soft yieldable material disposed in contact with and fitting the scalp of a wearer's head, and an outer hair-carrying layer 7 or exterior scalp cap of pliable material overlying and adhesively united with the inner layer 6.

30 The inner layer 6 is composed of a natural scalp coloured acid resistant plastic such as polyvinyl chloride, and in the inner surface of this layer there are formed a multiple number of relatively shallow circular cupped recesses 8, see Figs. 3 and 4.

35 Extending around the margin or perimeter of the inner layer 6, is a plain border 9 which is devoid of shallow circular recesses but is provided with fine apertures indicated by 10, the purpose of which will appear hereinafter.

40 The shallow circular recesses 8 are arranged in evenly spaced rows or series intersecting at right angles, and two rows of recesses 8a adjoining the plain border 9 are provided with relatively fine apertures 11 which extend through the layer 6 to the exterior surface thereof.

45 The circular recesses 8 situated inwardly of and bordered by the recesses 8a, are each provided with a centrally disposed drain vent or hole 12 of relatively greater diameter than the apertures 11.

50 Vents 13 of small cross-sectional area are also

provided near the border 9 and between the circular recesses 8a. The purpose of the vents 13 will be explained later.

The outer layer or exterior scalp cap 7 is composed of an acid resistant plastic, such as polymethyl methacrylate or polyvinyl chloride, which is pigmented to have a natural skin colour and has incorporated therein a fibrous filler.

Referring to Figs. 5 and 6, it will be observed that the outer layer 7 is substantially thicker than the inner layer 6 and that the former layer tapers inwardly from the edge as at 14 to the major portion or area 15 of the layer which is of substantially uniform thickness. The thickness at the edges is approximately one half the thickness over the major area 15.

Formed through the major portion 15 of the layer 7 are a multiple number of hair-receiving apertures 16 which at the inner side of the layer are enlarged or countersunk as at 17.

The hair-receiving countersunk apertures 16 are arranged in equally spaced rows or series which intersect at right angles, and interposed between and correspondingly spaced to the apertures 16 are drain vents or holes 18 which when the outer layer 7 is superimposed on the inner layer 6 as hereinafter described, become aligned with the vents or holes 12 in the inner layer so as to form continuous drainage outlets, see Fig. 8.

It will be apparent that the recesses 8, vents 12, hair-receiving holes 16 and drain holes 18 are respectively spaced at substantially the same distance apart.

Formed in the tapering marginal part 14 of the outer layer 7 are a multiple number of countersunk hair-receiving apertures 19 of less diameter or sectional area than the apertures 16.

The hair-receiving apertures 19 are arranged in evenly spaced rows or series but the distance between the apertures 19 is considerably less than the spacing of the apertures 16, the pitch of the former being as illustrated, approximately one-half the pitch of the latter.

Interposed between the spaced rows of hair-receiving apertures 19 are rows of small apertures 20, the pitches or distances between the former and latter apertures being equal and substantially the same as the pitch of the fine apertures or vents 10 and 13 in the inner layer 6.

Accordingly, it will be understood that when the outer layer 7 is placed over the inner layer 6, the apertures 20 align with the apertures or vents 10 and 13, to form small continuous ducts between the interior and exterior surfaces of the hair cap 5.

In order to facilitate the placing of the hair in the hair-receiving apertures 16 and 19, the hair of suitable length and in small bundles or groups 21 is placed within thin aluminium tubes 22 of appropriate diameters to snugly fit the apertures 16 and 19 and of requisite wall thickness or gauge so as to easily be bent or deformed.

The tubes 22 are of sufficient length to be bent and upset upon receiving the hair groups to form bases or enlargements 23 whereby the hair is fixed against displacement from the tubes and which are shaped to fit within the countersunk ends of the hair-receiving apertures and thereby secure the tubes and hair groups or bundles against dislodgment.

To permit the hair bundles 21 to be readily inserted through the hair-receiving apertures 16 upon being secured in the tubes 22 as above described, the hairs are wound taut and are stiffened and maintained in rod-like form by stearin

as shown at 21a Fig. 8. Upon the stiffened hair bundles being inserted through the apertures, the stearin is removed by a weakly alkaline soap solution.

Preferably though not essentially, each group or bundle 21 contains approximately 64 separate hairs, and the grouping of the hair-receiving apertures 16 in the major area portion 15 is such that approximately 64 hair groups or bundles 21 are provided per square inch of surface.

Accordingly in the area 15 of the hair cap the hair density is approximately 4000 hairs per square inch, thus being considerably in excess of the normal hair density of 1000 hairs per square inch.

The increased hair density of 4000 hairs per square inch arranged in groups forms a brush-like arrangement whereby tangling of the hair is lessened and deterioration or damage by combing is reduced.

As illustrated in Figs. 5 and 6, the hair-receiving apertures 19 are more closely spaced and accordingly more numerous per square inch in the tapering part 14, but the size of the apertures 19, as previously stated, is less than that of the apertures 16.

The hair groups or bundles for the more numerous apertures 19 of the tapering marginal areas 14 contain approximately 32 hairs, so that the hair density may be substantially uniform over the hair cap and a natural appearance may be achieved.

In the parting and side-board areas 24 (see Figs. 1 and 2), the hair groups or bundles are substantially the same size as and spaced similarly to the groups or bundles in the tapering border areas 14.

The parting area (not shown) is approximately one inch in width and extends for the natural length or distance, and this area and the side board areas 24 are devoid of vents or apertures and are of scalp colour in order to present a natural appearance.

The inner layer or interior scalp cap 6 and the outer layer or exterior scalp cap 7 constructed as above described, are assembled by placing the outer layer 7 over the inner layer 6 after the inner surface of the former and the outer surface of the latter have been rendered adhesive by an appropriate solvent, such as methylene dichloride.

Upon being pressed into contact, the inner and outer layers 6 and 7 become integrally united or bonded together to comprise the hair cap with the hair comprising the bundles 21 projecting outwardly from the apertures 16.

The small aligning drain vents 12 and 18 and the fine apertures 10 and 13 and the apertures 20 aligned therewith are preferably pierced through the layers 6 and 7 after the same have been assembled as above described, and prior to removal of the stearin from the stiffened hair bundles indicated by 21a.

The ventless areas, namely the marginal or border areas, the parting area and the side board areas, are punctured to resemble natural pores of the skin. Such fine apertures or pores provide outlets for vapour and excess perspiration.

The rear base line, indicated by 25, is shaped or contoured to conform with the wearer's anatomical formation so as to avoid chafing action apt to be caused by downward and backward movement of the head. The base line 25 is concealed by overlapping of the hair.

The frontal edges of the hair cap may be

designed to suit the age of the wearer by receding at the temples or otherwise in response to the wearer's desires.

In addition to the overlapping hair at the extreme frontal edges, a few hairs from each bundle or group may be cut to the desired length and spread by pressure to resemble natural irregularity or fine hairdown.

In order to shape the hair cap to conform with a user's scalp, the former is sufficiently heated to soften the plastic material, whereupon the hair cap is placed over and impressed upon the user's head.

In use, the hair cap is maintained firmly upon the user's head by retaining pressure applied in contact with the mastoid areas of the temporal bone and extending to the junction of the pinna of the ear with the scalp, as indicated at 26, see Fig. 1.

In order to apply such retaining pressure, the portions of the hair cap overlying the mastoid areas are formed as surface concavities or recesses which are devoid of hair groups and vents, so that upon these portions being pressed upon the scalp to expel the contained air from the concavities or recesses, a cavity suction is produced under external atmospheric pressure whereby the hair cap is secured against displacement.

The retaining pressure is applied to the mastoid areas only, the superficial contact on the scalp and facial areas being free of holding pressure. Accordingly, restriction of blood circulation and discomfort are avoided.

Superficial contact at the side board areas 24 contributes to a natural effect, and contact of such areas with the ears serves as a warning to the wearer in the event of the occurrence of undue backward movement of the hair cap, thus eliminating fear of detection and affording confidence.

In placing the hair cap upon the head, the wearer adopts a stooping position when applying the cap to the frontal region with the hair overlapping downwardly, and remains in the stooping position until pressure applied manually effects the fitting.

In order to aid removal of the hair cap, there is provided an instrument or cap-lifter 27 illustrated by Fig. 9.

The cap-lifter 27 is constructed of metal strip and comprises a hook 28 and a bent portion which comprises a handle or grip 29.

In using the cap-lifter, the wearer grips the handle 29 and inserts the hook 28 beneath the edge of the hair cap at the base line 25 and at or about the nucal groove indicated by 30, see Fig. 1.

By employing such an instrument, it is unnecessary to provide conspicuous frontal edges on the hair cap for manual gripping, and the frontal appearance is permanently preserved and protected from injury. Any wear resulting from the use of the instrument is not visible and is moreover, concealed by the overlapping hair.

A hair cap constructed and fitted as above described, covers the whole hair growing area of a wearer's head, has a close fitting bonnet effect, does not chafe a wearer's head and conforms with the normal expansion and contraction of the scalp.

Moreover, the cupped recesses on the inner side of the hair cap are interdraining and the drain vents or holes extending outwardly from the cupped recesses afford outlets for perspiration and vapour. The ventless border in conjunction

with the inwardly situated recesses and vents, permits a controlled seepage of perspiration from the scalp particularly at the forehead areas, and the ventless border further enables the hair groups to be located closer to the edges so as to conceal the areas which include the drain vents and hair group bases not obscured by the spread of hair over the whole area of the hair cap exclusive of the outer edges.

Furthermore, as the hair cap is comprised of non-absorbent acid resistant plastic, the wearer is able to wash and bathe without removal of the hair cap.

If required, repairs may be effected by placing the hair cap upon a heated mould, so as to permit the inner and outer layers of the cap to be separated and any damaged or worn hair groups to be removed and replaced by new hair groups, whereupon the layers are reassembled as previously described herein.

The hair cap herein described and illustrated is, in effect, a false scalp having hair attached thereto and adapted for both male and female use. In order that the hair cap may function properly as a false scalp, it is essential that the whole hair growing area of a wearer's head be shaved and maintained so by the wearer, who is able to readily remove the hair cap and wash the interior thereof and his scalp as and when required, thereby maintaining cleanliness and a general feeling of natural freshness.

I claim:

1. A hair cap for a bald or sparsely-haired head comprising an inner scalp-fitting layer of a soft flexible non-absorbent acid resistant plastic fitting the normal hair growing area of the head, spaced rows of shallow draining depressions in the inner surface of the scalp-fitting plastic layer, an outer layer of flexible plastic material overlying and adhesively united with the inner scalp-fitting layer, spaced rows of apertures in the outer plastic layer, groups of hair mounted in and projecting from the apertures, and drain vents extending inwardly through the outer and inner layers and communicating with the shallow draining depressions.

2. A hair cap for a bald or sparsely-haired head comprising an inner scalp-fitting layer of a soft flexible non-absorbent acid resistant plastic fitting the normal hair growing area of the head, a ventless border extending about the margin of the inner scalp-fitting layer, spaced intersecting rows of shallow circular recesses formed in the inner surface of the scalp-fitting layer inwardly of the ventless border, an outer layer of flexible plastic material overlying and adhesively united with the inner scalp-fitting layer, a tapering marginal portion bordering the outer layer, spaced intersecting rows of countersunk apertures in the outer layer, spaced intersecting rows of countersunk apertures in the tapering portion of the outer layer more closely spaced and of less size than the former countersunk apertures, groups of hair mounted in and projecting from the apertures, and rows of drain vents through said layers interposed between the rows of countersunk apertures and communicating with the shallow circular recesses.

3. A hair cap for a bald or sparsely-haired head according to claim 2, having a thin deformable metal tube to fit each countersunk aperture and contain a hair group, a bend in the metal tube securing the hair group in the latter, and an enlarged head on the deformable tube fitting within the countersink recess of the

countersunk aperture and securing the tube and hair group in said outer layer.

4. A hair cap for a bald or sparsely haired head according to claim 2, having the portions overlying the mastoid areas of the head devoid of apertures and comprising vacuum chambers whereby the hair cap is suctionally maintained upon the head.

5. A hair cap for a bald or sparsely-haired head, comprising an inner scalp-fitting layer constructed of polyvinyl chloride and fitting the normal hair growing area of the head, a ventless border extending about the margin of the inner scalp-fitting layer, spaced intersecting rows of shallow recesses formed in the scalp contacting face of said inner layer inwardly of the ventless border, an outer layer constructed of polyvinyl chloride and overlying and adhesively united with the inner scalp-fitting layer, said outer layer comprising a major portion of uniform thickness bordered by a tapered marginal portion having at the edge a thickness one half the thickness of the major portion, spaced intersecting rows of countersunk apertures in said

major portion, spaced intersecting rows of countersunk apertures in said tapering portion more closely spaced and of less size than the countersunk aperture in said major portion, thin aluminium tubes containing groups of hair fitting the countersunk apertures, bends in the aluminium tubes securing the hair groups, headed enlargements of the aluminium tubes fitting the countersunk recesses of the countersunk apertures and securing said tubes and hair groups in the outer layer, ventless vacuum chambers formed in said inner layer in the portions of the latter overlying the mastoid areas, and rows of drain vents extending through said layers and communicating with the shallow recesses.

GEORGE FREDERICK HULL.
